UNITED STATES PATENT OFFICE.

GUSTAVE BURKHARDT, OF CHICAGO, ILLINOIS.

DESIGN FOR A BOWLING-ALLEY LIGHT-REFLECTOR AND PIN-INDICATOR.

SPECIFICATION forming part of Design No. 33,563, dated November 13, 1900.

Application filed August 13, 1900. Serial No. 26,795. Term of patent 14 years.

To all whom it may concern:

Be it known that I, GUSTAVE BURKHARDT, a citizen of the United States, residing at Chicago, in the county of Cook and State of Illinois, have invented and produced a new and original Design for a Bowling-Alley Light-Reflector and Pin-Indicator, of which the following is a specification, reference being had to the accompanying drawings, forming a part hereof.

Figure 1 is a perspective view of the reflector and pin-indicator, showing my original design. Fig. 2 is a front view showing the pin-indicator.

As shown in the drawings, the leading feature of my design consists of a generally-pyramidal body having on one side thereof a device indicating the usual position of tenpins when set up in a bowling-alley. This body

is formed by two long sides A and B and two short sides or ends C and D, which are connected at their adjacent edges and inclined upwardly and inwardly to a collar E at the top of the body and surrounding an opening therein.

On one side of the body is a pin-indicator which has a triangular-shaped face F, provided with a series of openings G.

Having thus fully described the design, what I claim is—

The design for a bowling-alley light-reflector and pin-indicator, substantially as shown and described.

GUSTAVE BURKHARDT.
